CONDENSER FOR STEAM CLOTHESPRESSES

Alphonse Ball, Sacramento, Calif.

Application May 27, 1935, Serial No. 23,795

6 Claims. (Cl. 257—36)

This invention relates generally to the garment pressing art, and is directed specifically and particularly to a condenser system for a steam garment press.

5 In the operation of steam garment presses, a large amount of steam is exhausted from the press. This steam must either be piped to an outlet exteriorly of the building or allowed to escape into the room causing dampness etc. In 10 many cities, it is unlawful to allow the steam to escape into the building and it must be piped out in the manner hereinbefore stated. However in crowded business districts it is often impossible to find such proper exterior outlet. 15 Also this continuous escape of the steam is wasteful.

It is therefore my principal object to provide a steam condenser which is adapted to be connected to the steam outlet of the press and which 20 prevents escape of the steam and condenses the same.

It is also my object to provide a condenser which when in operation will materially increase the vacuum in the buck of the press when the 25 steam pressure from the boiler is being bypassed to create such vacuum.

As a further object, it is my purpose to provide suitable means whereby the water derived from the steam may, while still hot, be pumped back 30 into the boiler.

A further object of the invention is to produce a simple and inexpensive device and yet one which will be exceedingly effective for the purpose for which it is designed.

35 These objects I accomplish by means of such structure and relative arrangement of parts as will fully appear by a perusal of the following specification and claims.

In the drawing similar characters of reference indicate corresponding parts in the several views:

Figure 1 is a diagrammatic view illustrating my condenser as connected in combination with a steam garment press and steam boiler.

45 Figure 2 is a plan view of one of the condenser plates employed in the condenser.

Referring now more particularly to the characters of reference on the drawing, the steam for the press is produced in the usual boiler 1 having an injection pump 2 connected to the water inlet pipe 3 leading to the lower end of the boiler. Mounted adjacent this pump 2 is the water supply bucket 4 which is connected to the pump by a water supply pipe 5. Interposed 50 in this pipe 5 are two selectively operable valves

6 and 7 between which is mounted a water glass 8 in connection with said pipe.

A steam supply pipe 9 leads from the boiler to the press. The boiler is also provided with a safety valve 10 and drain pipe 11 leading to the 5 water supply bucket 4 from the safety valve.

The steam garment press comprises the ordinary buck 12 and presser head 13 hinged behind the buck as at 14. A suitable stand 15 supports the press above the floor in operative 10 position.

The steam supply pipe 9 leads into the buck 12 and supplies steam thereto in the usual manner—a valve 16 in the pipe 9 regulating the flow of steam into the buck. An exhaust pipe 17 15 leads from the buck and extends into the condenser as will be hereinafter seen. A branch pipe or by-pass pipe 18 with a control valve 19 therein leads from the supply pipe 9 on the boiler side of valve 16 to a connection with the pipe 20 17 at an acute angle therewith in the direction of flow of the steam. Therefore, when the steam flows through the by-pass a vacuum will be created in the pipe 17 ahead of the by-pass pipe. The above is also customary in steam presses. 25

The condenser comprises a closed cylindrical shell 20 supported in upstanding relation on a stand 21. The exhaust pipe 17 enters the condenser cylinder at 22 and discharges downwardly beyond the center of the cylinder as at 23. 30

Rigidly and horizontally mounted in the condenser cylinder above the pipe 17 is a plurality of circular condenser plates 24 vertically spaced as illustrated. Each of these condenser plates is in the form of a circular grate as illustrated 35 in plan in Figure 2, some of these plates having a central circular opening 25 while the plates mounted immediately above the pipe 17 are solid in this central portion as at 26. These plates are preferably formed of aluminum although they 40 may be formed of any metal having high heat conductivity as one of its characteristics.

Extending through and depending from the upper end of the condenser shell is a vent pipe 27 which extends down only part way into the 45 condenser to a termination in a funnel shaped hood 28 which is positioned adjacent but above the lowest condenser plate having a central opening 25 therein. This hood is provided with a screen 29 on the lower end thereof.

A water return line 30 extends from the lower portion of the condenser to a connection with the water supply pipe 5 at a point between the valve 7 and pump 2.

In actual practice, the condenser will be 10- 55

cated immediately behind the press rather than beyond one end thereof as illustrated diagrammatically in Figure 1. This not only permits compactness of assembly but also makes for efficiency of operation as will hereinafter appear.

Operation

In operation the steam generated in the boiler passes through the pipe 9 up to the valves 16 and 19 which, when the press is not being operated, are closed.

When a garment is to be pressed, it is placed on the buck, the head closed and valve 16 opened allowing steam to pass into the buck and permeate through the same to the garment. All excess steam passes out through pipe 17 into the condenser.

After the garment is properly steamed, the valve 16 is closed and valve 19 opened thereby allowing the steam to by-pass through pipe 18 into the condenser. The velocity of the steam passing through this pipe creates a vacuum in pipe 17 which results in a vacuum in the buck. The vacuum in the buck draws outside or cool air through the garment drying the same.

Thus, regardless of the purpose which the steam is serving (to steam garments or create vacuum) at any particular time, the steam after being used is exhausted into the condenser and creates a circulation of steam in said condenser. With the discharge outlet 23 off center, as shown, the desired circulation within the condenser is assured. Also, discharging the steam downward onto the condenser aids in condensation of the steam entering the condenser.

The condenser plates being of aluminum or other metal having high heat conductivity characteristics, quickly absorb the heat of the steam causing its condensation, the condensate accumulating at the bottom of the condenser.

Any uncondensable gas such as air with any remaining vapor leaves the condenser through the vent pipe 27. The relatively fine screen 29 in the hood 28 prevents too rapid a discharge of the vapor. The central solid portions 26 of the plates 24 between the pipe 17 and hood 28 prevent the steam as it initially enters the condenser from at once being carried up and out the vent pipe. These solid portions force the steam to circulate and therefore condense as it passes through the grate-like condenser plates.

The combination disclosed has many advantages as heretofore suggested. It not only prevents the undesirable escape of steam but also condenses the same for re-use while still hot, thereby eliminating cooling of the boiler by the injection of cold water. This saves a great deal of time and materially reduces the fuel cost, and as distilled water is often used in such boilers, the water may be used over and over instead of continually using a fresh supply of water.

The quantity of water in the condenser is recorded on the water glass 8 when valve 7 is open. The pump 2 is used, as is obvious, to inject either the hot water condensed from the steam carried back through pipe 30, or fresh cold water from bucket 4 into the boiler (both valves 6 and 7 being opened in the latter instance).

A further advantage of my combination is the fact that the condenser, especially when located close to the press—preferably immediately behind the same—causes a material increase in the vacuum created in the buck when the steam is being by-passed for that purpose.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention, what I claim as new and useful and desire to secure by Letters Patent is:

1. A steam condenser for a steam garment press comprising a closed vertical shell, a steam discharge pipe extending from the press into the lower portion of the shell, a vent pipe extending out of the shell from the upper portion thereof, and a plurality of vertically spaced grate-like condenser plates mounted in the shell above said discharge pipe.

2. A device as in claim 1 in which the condenser plates are formed of aluminum.

3. A device as in claim 1 in which the condenser plates are formed from a metal characterized by a high heat conductivity.

4. A steam condenser for a steam garment press comprising a closed vertical shell, a steam discharge pipe extending from the press into the lower portion of the shell, a plurality of vertically spaced grate-like condenser plates mounted in the shell above the steam discharge pipe, a number of said plates immediately above said pipe having a central solid portion, the remainder of the plates having a central opening therein and a vent pipe extending centrally through the upper end of the shell and depending into the shell through the central openings of a plurality of said last named plates.

5. A device as in claim 4 in which the lower end of the vent pipe is formed with a funnel shaped hood and a screen over the mouth of said hood.

6. A device as in claim 4 in which the steam discharge pipe opens downwardly toward the bottom of the shell and is offset from the center of said shell.

ALPHONSE BALL. 60
